ROTARY TILLER

Oscar L. Meeks, Scranton, Pa., assignor, by mesne assignments, to The Sperry Corporation, New York, N. Y., a corporation of Delaware

Application January 8, 1948, Serial No. 1,153

5 Claims. (Cl. 97—40)

1

My invention relates broadly to agricultural machinery and more particularly to an improved construction of a rotary tiller.

One of the objects of my invention is to provide a simplified construction of a rotary tiller which eliminates the use of gears, and yet which is very effective to cut up and mix the ground thoroughly throughout the full length of the rotor mechanism.

Another object of my invention is to provide a construction of a rotary tiller in which a composite drive is employed from the power source to the rotor including a shaft, a V-belt system, and a chain drive system.

Another object of my invention is to provide an arrangement of overload clutch for use in rotary tillers whereby sudden stoppage or overload of the rotor, which might occur should the rotor encounter a stump or heavy stone obstruction, will offer minimum injury to the machine.

A further object of the invention is to provide an arrangement for a hydraulic lift for elevating the rotor of the rotary tiller from the ground.

Still another object of my invention is to provide an improved construction of rotor for a rotary tiller in which the rotary tiller teeth may be manufactured inexpensively on a mass production scale and provide an effective means for cutting and grinding the ground thoroughly throughout the full length of the rotor.

A further object of my invention is to provide an improved means for spacing the sections of the rotor on the rotor shaft of the rotary tiller mechanism.

Still another object of my invention is to provide an improved arrangement of adjustable hood for coaction with the rotor of a rotary tiller.

Other and further objects reside in providing an improved mounting means for the movable parts of a rotary tiller and an improved drive system for a rotary tiller, as set forth more fully in the specification hereinafter following, by reference to the accompanying drawings in which:

Figure 1 is a side elevational view of a tractor driven rotary tiller embodying the principles of my invention;

Fig. 2 is a top plan view of the rotary tiller shown in Fig. 1;

Fig. 3 is an enlarged cross sectional view of the rotary tiller showing the hydraulic lift associated therewith and the adjustable hood which coacts with the rotary tiller, the rotary tiller being shown in lowered position for tilling operation;

Fig. 4 is a view similar to the view illustrated

in Fig. 3, but showing the rotary tiller in elevated position with the tiller raised out of tilling position;

Fig. 5 is an enlarged transverse sectional view taken substantially on line 5—5 of Fig. 2;

Fig. 6 is an enlarged transverse sectional view taken substantially on line 6—6 of Fig. 2;

Fig. 7 is a longitudinal sectional view taken through the rotary tiller shaft and illustrating the supporting members for the tiller teeth in section;

Fig. 8 is a side elevational view of one of the tiller sections embodied in the rotary tiller of my invention;

Fig. 9 is a cross sectional view taken substantially on line 9—9 of Fig. 8;

Fig. 10 is an enlarged transverse sectional view taken on line 10—10 of Fig. 6;

Fig. 11 is a side elevational view of one of the tiller sections, the spacing member associated with the tiller section being partially broken away and illustrated in section;

Fig. 12 is a perspective view of one form of the tiller teeth embodied in the structure of my invention;

Fig. 13 is a perspective view of another form of the tiller teeth embodied in the structure of my invention;

Fig. 14 is a fragmentary sectional view taken substantially on line 14—14 of Fig. 3;

Fig. 15 is a transverse sectional view taken substantially on line 15—15 of Fig. 3;

Fig. 16 is a fragmentary elevational view showing the manner of associating the rotary tiller with the hydraulic lift mechanism; and

Fig. 17 is an enlarged transverse sectional view taken on line 17—17 of Fig. 16.

Referring to the drawings in detail, reference character 1 designates the chassis of a tractor driven rotary tiller which is supported on wheels 2 and provided with a coupling means 3 for connection to a tractor. The chassis 1 supports a suitable prime mover, indicated at 4 as a gasoline engine, which is controlled through suitable lever controls 5 from the operator's position. Fuel supply tank 6 is provided on chassis 1. Engine 4 drives the main shaft 7 which carries a pulley 8 thereon which drives a multiplicity of V-belts 9 operating over the pulley 10 mounted on countershaft 11 journaled on chassis 1. The pulley 10 is driven by the V-belts 9 operating over the power driven pulley 8. The V-belts 9 are suitably protected and guarded by guard member 12. The overload clutch is provided between countershaft 11 and the driving pulley 10, which I have repre-

sented as including the clutch plate 14 carried on sleeve 14a keyed to countershaft 11 and establishing frictional connection with the driving face 12a of driven pulley 10. The clutch face 15 is provided on the opposite side of the face portion 10b of pulley 10 and establishes frictional contact with pressure plate 18 carried by countershaft 11 and pressure plate 16. Pressure plate 18 is keyed to shaft 11 and continuously presses pressure plate 16 toward the face 10b of pulley 10 for ensuring a driving connection between pulley 10 and countershaft 11 for all normal driving loads. However, upon increase in driving load, which may occur by sudden loads placed upon countershaft 11, the clutch parts slip, enabling driving shaft 7 to continue to revolve, while pulley 10 slips with respect to the countershaft 11.

The countershaft 11 carries a multiple sprocket wheel 19 on the opposite end thereof operatively engaged with sprocket chains 20 which engage over correspondingly aligned sprocket wheels 21 carried by the end of the rotary tiller shaft 11. The sprocket chains 20 are protected by the housing or guard 23 eliminating the possibility of external contact with the moving parts of the drive chain.

The rotary tiller shaft 22 is journaled at opposite ends in a pair of angularly shiftable spaced arms or levers 24 and 25 which are pivotally mounted with respect to countershaft 11 as a center, and free to be angularly adjusted in position with respect thereto by the hydraulic lift mechanism represented at 26, as will be more fully described hereinafter. The rotary tiller shaft 22, thus being swingable in an orbit about countershaft 11 as a center, may be raised or lowered with respect to the surface of the ground, indicated generally at 21. The rotary tiller shaft 22, intermediate the opposite ends thereof, is of polygonal cross section for the purpose of keying the rotary tiller sections thereto. The rotary tiller sections are illustrated more clearly in Figs. 8-13, from which it will be seen that each rotary tiller section includes a tine plate section 28 of polygonal contour having a central hub portion 29 of tubular section with a contour corresponding to the section of the rotary tiller shaft 22. The central hub portion 29 serves as a spacing member for each tiller section so that a multiplicity of the hub connected tine plates 28 may be stacked adjacent each other on the rotary tiller shaft 22 for spacing the rotary tiller tools, carried by the tine plates 28, uniformly along the rotary tiller shaft. In the form of my invention shown, the rotary tiller shaft 22 is of square section and each of the spacing hubs 29 is of similar square section and is thus keyed to revolve with the rotary tiller shaft 22.

The tine plates 28 carry rotary tiller tools of two differing forms represented at 30 in Fig. 12 and at 31 in Fig. 13. The rotary tiller teeth 30 are offset with respect to the rotary tiller teeth 31 so that, by alternating the circumferential arrangement of the rotary tiller teeth, rotary tiller sections are built up with the rotary tiller teeth longitudinally spaced with respect to the rotary tiller shaft 22. In order to symmetrically balance each of the rotary tiller sections the rotary tiller teeth are mounted in groups on the tine plates with the tines of the different types mounted in diametrically opposite positions and diagonally disposed with respect to opposite sides of the plates. That is to say, in Fig. 9 the rotary tiller member 30, of offset construction, is secured by bolts 30a to tine plate 28 in a radial position,

while an oppositely arranged tiller tool, represented by reference character 31, is secured in a diagonally opposite position on tine plate 28 by means of bolts 31a.

Referring to Figs. 8, 10 and 11, it will be seen that this arrangement is successively carried out for each of the diametrically arranged sets of rotary tiller tools 30 and 31. Referring to Fig. 8, it will be seen that rotary tiller tool 30, moving in a clockwise direction, has adjacent thereto a rotary tiller tool 31, while, continuing in a clockwise direction, rotary tiller tool 31 has adjacent thereto a rotary tiller tool 30. Correspondingly, continuing in a clockwise direction, rotary tiller tool 30 has a rotary tiller tool of the type represented by 31 adjacent thereto, and, following through the balance of the rotor system, in the same clockwise direction, it will be seen that a tool of the type 30 is arranged adjacent to the tool 31, and, likewise continuing in a clockwise direction, a tool of the type 31 follows the tool 30. Thus, symmetrically arranged and balanced, rotary tiller sections are formed by tine plates 28 and the series of rotary tiller tools 30 and 31, which constitute tines with respect thereto. As represented in Figs. 6 and 7, these rotary tiller section assemblies are uniformly distributed throughout the whole length of the rotary shaft 22, so that, when positively driven over the ground, the tines cut up the ground, as represented particularly in Fig. 3, and mix the ground thoroughly the full length of the rotor.

The rotary tiller shaft 22, supported in the angularly movable arms 24 and 25, is angularly adjusted with respect to the surface of the ground 27 by means of a supporting roller member 32 carried by shaft 23 which is journaled at opposite ends on arms 34 pivotally mounted on the transverse member 35 connected with chassis 1. The arms 34 are adjustably connected through link members 36 with the brackets 37 extending from the laterally extending member 38 and extending between arms 24 and 25. Links 36 have a plurality of adjusting apertures 36a therein which permit adjustable connection to be made to brackets 37 for thereby regulating the spacial distance between arms 24 and 25 and roller 32 for correspondingly determining the depth of penetration of the rotary tiller tools or tines 30 and 31 into the earth 27.

The hydraulic lift mechanism, referred to hereinbefore at 26, includes an operating cylinder into which the hydraulic fluid is introduced under control of the control valves, represented at 39, in the operator's position on chassis 1. Piston member 40 of the hydraulic lift mechanism connects to the lever arms 41 secured to the cylindrical sleeve 42 which extends over the housing 41 which encloses countershaft 11. The sleeve 42 carries spaced lever arms 44 thereon which extend rearwardly substantially in the direction of the rotary tiller shaft 22. The ends of the arms have link chain members 45 which connect to the spaced bracket members 37 carried by the laterally extending channel member 38. Thus, a lifting force may be applied to the arms 24 and 25 which connect to the opposite ends of the laterally extending member 38 for raising or lowering the rotary tiller when it is desired to move the machine from one location to another. The raised position of the machine is illustrated in Fig. 4 as distinguished from the lowered position of the machine illustrated in Fig. 3.

The hood 47, which extends over the rotary tiller, is spacially related to the rotary tiller tools

or teeth 30—31, enabling considerable churning and development of the earth while confining the area from which the earth is removed. The hood 47 extends the entire length of the rotary tiller shaft and substantially encloses the rotary tiller shaft and the tools or tines thereon. The hood 47 is reinforced longitudinally by ribs 48 for imparting sufficient rigidity to the hood to withstand considerable strain. The rear cover of the hood is formed by a plurality of foldable sections 47a and 47b connected through hinges 47d and 47e with the main structure of the hood 47. This permits the sections of the hood to be raised for access to the rotor mechanism beneath the hood. Opposite ends of the hood are supported between 15 arms 49 which are pivotally mounted at their ends on an axis passing through countershaft 11. The hood 47 may be shifted with respect to rotary tiller shaft 22 by reason of the slotted connection of the ends of the hood 47 with the rotary tiller shaft 22, as represented at 47c to allow for limited adjustment of the hood with respect to the rotary tiller shaft. This is accomplished by adjusting the screw member 50 through crank 51. Screw member 50 is screw threaded through 25 screw threaded member 52 carried by arm 49 to provide an adjustable bearing against plate 53 carried by laterally extending member 38 to effect the required adjustment. It will be understood that similar adjusting means are associated with each side of the assembly, as shown in the symmetrical arrangement illustrated in Fig. 2. Thus, the elevation of the hood 47 with respect to the rotary tiller tools or tine plates 30—31 may be controlled within limits. All bearings on the 30 equipment are of the roller type and large enough to assure long life. The machine is mounted on two wheels of ample size to carry the load and the relationship of the wheels to the rotor is such that no tracks are left on the finished pulverized 35 earth.

I have found the rotary tiller construction of my invention highly practical in manufacture, production and operation, and, while I have described one of the preferred embodiments of my invention, I realize that modifications may be made, and I intend no limitations upon my invention other than may be imposed by the scope of the appended claims.

What I claim as new and desire to secure by 50 Letters Patent of the United States is as follows:

1. In a power driven tiller, a frame structure, a transverse drive shaft journaled in said frame structure, a sleeve member extending concentrically with respect to said shaft and carrying 55 spaced levers thereon for supporting a rotary tiller at the extremities thereof driven from said drive shaft, means for rocking said sleeve member for angularly adjusting said levers and correspondingly controlling the position of said rotary tiller with respect to the surface of the earth, a hood forming a cover for said rotary tiller, a pair of spaced arms pivotally mounted on said drive shaft, connections between said arms and the ends of said hood, a bearing plate connected with each of said spaced levers, adjusting screws carried by said spaced arms and extending in vertical alignment with said bearing plates and adjustable with respect thereto for selectively controlling the angular relation of said 60 spaced arms with respect to said spaced levers and correspondingly controlling the spacial relation of said hood and said rotary tiller.

2. In a power driven tiller, a frame structure, a transverse drive shaft journaled in said frame 75

structure, a sleeve member extending concentrically with respect to said shaft and carrying spaced levers thereon for supporting a rotary tiller at the extremities thereof driven from said drive shaft, a channel shaped member extending between said spaced levers intermediate the rotary tiller and the connections of said spaced levers with said sleeve member, means for rocking said sleeve member for angularly adjusting said levers and correspondingly controlling the position of said rotary tiller with respect to the surface of the earth, a hood forming a cover for said rotary tiller, a pair of spaced arms pivotally mounted on said drive shaft, connections between said arms and the ends of said hood, bearing plates carried by said channel-shaped member in a position adjacent the vertical plane of operation of said levers, adjusting screws carried by said spaced arms and extending in vertical alignment with said bearing plates and adjustable with respect thereto for selectively controlling the angular relation of said spaced arms with respect to said spaced levers and correspondingly controlling the spacial relation of said hood and said rotary tiller.

3. In a power driven tiller, a frame structure, a transverse drive shaft journaled in said frame structure, a sleeve member extending concentrically with respect to said shaft and carrying spaced levers thereon for supporting a rotary tiller at the extremities thereof driven from said drive shaft, a transverse member extending between said spaced levers intermediate the rotary tiller and the connections of said spaced levers with said sleeve member, means for rocking said sleeve member for angularly adjusting said levers and correspondingly controlling the position of said rotary tiller with respect to the surface of the earth, a hood forming a cover for said rotary tiller, a pair of spaced arms pivotally mounted on said drive shaft, connections between said arms and the ends of said hood, bearing plates carried by said transverse member in a position adjacent the vertical plane of operation of said levers, adjusting screws carried by said spaced arms and extending in vertical alignment with said bearing plates and adjustable with respect thereto for selectively controlling the angular relation of said spaced arms with respect to said spaced levers and correspondingly controlling the spacial relation of said hood and said rotary tiller.

4. In a power driven tiller, a frame structure, a transverse drive shaft journaled in said frame structure, a sleeve member extending concentrically with respect to said shaft and carrying spaced levers thereon, said levers extending in a rearward and downward position for supporting a rotary tiller at the extremities thereof driven from said drive shaft, a pair of spaced arms pivotally mounted on said drive shaft and projecting rearwardly and downwardly in a plane substantially above the plane of said spaced levers whereby the planes of said pair of levers and said pair of arms intersect with said transverse drive shaft as a center and form a V-shaped section viewed from either side thereof, a hood forming a cover for said rotary tiller, connections between said pair of spaced arms and the ends of said hood, means for rocking said sleeve member for angularly adjusting said levers and correspondingly controlling the position of said rotary tiller with respect to the surface of the earth, and separate means for adjusting the spacial relation between said levers and said arms for increasing or decreasing the angle of said

V-shaped section, and correspondingly controlling the spacial relation of said hood and said rotary tiller.

5. In a power driven tiller as set forth in claim 4, in which said separate means for adjusting the spacial relation between said levers and said arms each consists of rotatable screw members carried by said arms and operative to be advanced or retracted toward said spaced levers for elevating or lowering said hood with respect to said rotary tiller. 10

OSCAR L. MEEKS.
